ARTICLE FORMING APPARATUS

Frank A. Schultz, Chicago, Ill., assignor to Western Electric Company, Incorporated, New York, N. Y., a corporation of New York

Application December 9, 1938, Serial No. 244,773

1 Claim. (Cl. 18—42)

This invention relates to article forming apparatus, and more particularly to a sectional mold or die for molding telephone handset handles.

An object of the invention is to provide a simple and inexpensive sectional mold or die for forming articles from plastic materials.

In accordance with the above object, one embodiment of the invention contemplates the provision of a sectional mold or die for molding telephone handset handles having re-entry outside contours, the said die being split into a plurality of sections which are readily separable to permit the removal of the molded handle therefrom, the design and arrangement of the die sections being such that no additional molding flashes result from the split construction.

Other features and advantages of the invention will become apparent from the following detailed description when read in conjunction with the accompanying drawings, in which:

Fig. 1 is a vertical sectional view of a punch and die for molding telephone handset handles, the die being of a split construction embodying the features of the invention;

Fig. 2 is a sectional view taken on line 2—2 of Fig. 1;

Fig. 3 is a fragmentary sectional view taken on line 3—3 of Fig. 1;

Fig. 4 is a plan view of the sectional dies with the several sections thereof separated from each other;

Fig. 5 is a sectional view taken on line 5—5 of Fig. 4, and

Fig. 6 is an elevational view of a telephone handset handle adapted to be molded by the punch and die illustrated in Figs. 1 to 5, inclusive.

The invention is herein illustrated and described as embodied in a sectional die for molding telephone handset handles of the type shown in Fig. 6, which comprises two substantially semi-spherical portions 10 and 11 interconnected by a handle portion 12. The semi-spherical portion 10 is externally threaded, as indicated at 13, for receiving a transmitter cap 14 shown in dotted outline in Fig. 6, and the other semi-spherical portion is similarly threaded, as indicated at 15, for receiving a receiver cap 16, also shown in dotted outline in Fig. 6.

Referring now to Figs. 1, 2 and 3 of the drawings, there is illustrated therein a multi-section molding die 20 and a cooperating punch 21 adapted to mold the telephone handset handle shown in Fig. 6. The punch is of conventional one-

piece construction and may be attached as usual to a punch plate 22 which is adapted to be fixed to the upper platen of a suitable molding press (not shown).

5 The multi-section die may be removably supported in a cavity 24 of a die supporting yoke 25 which is attached to the lower platen of the press. The usual ejector pins, such as indicated at 27, may be provided for automatically removing the die from the cavity of the supporting yoke upon separation of the punch from the die. The general construction and arrangement thus far referred to is well known in the art and, therefore, no further description thereof is believed necessary to a complete understanding of the present invention.

In accordance with a feature of the present invention, the die 20 is split, as shown, into three readily separable sections 28, 29 and 30. The central section 29 is substantially T-shaped in cross section and the sections 28 and 30 are formed with recesses 31 and 32, respectively, (Fig. 4) in their interengaging surfaces for embracing the depending portion 34 of the central die section. A pair of pins 35, 35 project laterally from both sides of the depending portion of the central die section and are receivable in apertures 36, 36 in the die sections 28 and 30 for the purpose of accurately aligning the several sections 30 of the die.

The die sections 28 and 30 are each provided at one end with a semi-circular recess 37 and at their opposite ends with a semi-circular recess 38. The recesses 37 cooperate to form a circular recess for receiving an internally threaded ring 40 which serves to mold the thread 13 on the transmitter cap receiving portion of the telephone handset handle. The recesses 38 cooperate to form a circular recess for receiving an internally threaded ring 42 for molding the thread 15 on the receiver cap portion of the handle.

45 A removable insert 44 is coaxially supported within the threaded ring 40 with its upper end portion projecting above the threaded ring and suitably shaped to impart the desired configuration to the interior of the semi-spherical transmitter end 10 of the handset handle. A depending reduced shank portion of the insert 44 has a radially projecting pin 47 which extends into a slot formed by cooperating notches 48, 48 in the interengaging surfaces of the die sections 28 and 30. This prevents turning or angular displacement of the insert during the molding operation.

50 A removable insert 50, similar to insert 44, is

coaxially supported within the threaded ring 42 with its upper end portion projecting above the threaded ring and suitably shaped to impart the required configuration to the interior of the semi-spherical receiver end 11 of the handset handle. The insert 50 is locked against angular displacement by a pin and slot arrangement which is similar to that described above in connection with the insert 44.

In the operation of the apparatus, the die sections and inserts are assembled together and placed in the cavity 24 of supporting yoke 25, as shown in Figs. 1 to 3, inclusive. The required amount of molding material is then placed in the die, after which the material is compressed between the punch and die. By the simultaneous application of heat and pressure the material is molded into a homogeneous handset handle having the desired shape and contour imparted thereto by the punch and die. The punch and die are then separated from each other and simultaneously therewith the die may be lifted out of its supporting yoke cavity by means of the ejector pins 21. Next, the molded handle is removed from the die within which it is retained upon separation of the punch from the die. This is easily and quickly accomplished when employing the split or multi-section die construction of the present invention. For example, the die sections 28 and 30 are first separated from each other and from the central die section 29, as shown in Fig. 4. The inserts 44 and 50 are then easily removed, after which the threaded rings 40 and 42 are readily unscrewed from the transmitter and receiver end portions, respectively, of the molded handle. The molded handle

is now free to be separated from the central die section 29.

In the molding of the handle, a thin fin or so-called molding flash, such as indicated at 60, is formed at the parting line between the punch and the die members. This is removed preferably by cutting it away by means of a tool adapted to leave a uniform groove in place of the fin, as indicated at 62 in Fig. 6.

It will be noted that no additional fins or molding flashes result from the split or multi-section construction of the die, since the molding material is not exposed to any of the parting lines between the die sections 28, 29 and 30 and, therefore, the parting lines between these die sections do not produce any fins or molding flashes.

It should be understood that the invention is not limited to the particular embodiment thereof herein illustrated and described, except insofar as is defined by the appended claim.

What is claimed is:

In an apparatus for molding telephone handset handles having a semi-spherical portion at each end thereof, a split molding die comprising a central section having a reduced depending portion, a pair of complementary sections having recessed central portions for embracing said depending portion and end portions having semi-circular recesses cooperating to provide a circular recess at each end of the die, and a removable threaded ring fitting in each of said circular recesses for molding a screw thread on each of the semi-spherical end portions of the handset handle.
